INVENTOR

UNITED STATES PATENT OFFICE.

WILLIAM J. PUBLOW, OF DETROIT, MICHIGAN, ASSIGNOR TO THE FARRAND COMPANY, OF DETROIT, MICHIGAN, A CORPORATION OF MICHIGAN.

PNEUMATIC-ACTION FOR AUTOMATIC PIANOS.

No. 891,951.

Specification of Letters Patent.

Patented June 30, 1908.

Application filed September 14, 1907. Serial No. 392,916.

To all whom it may concern:

Be it known that I, WILLIAM J. PUBLOW, a citizen of the United States of America, residing at Detroit, in the county of Wayne 5 and State of Michigan, have invented certain new and useful Improvements in Pneumatic-Actions for Automatic Pianos, of which the following is a specification, reference being had therein to the accompanying drawings. 10 It is the object of the invention to condense the construction so as to occupy as small a space as possible within the piano case, and at the same time to obtain a positive and efficient action. This object I attain by certain features of construction as hereinafter set forth.

In the drawings, Figure 1 is a vertical cross section through the action; Fig. 2 is a perspective view of the parts detached; and 20 Fig. 3 is a section on line $x-x$, Fig. 1.

My improved action is of that type in which pouches are used for the primary and secondary pneumatics, and the power or key, actuating pneumatic is of the bellows type. 25 With such constructions, the primary and secondary pneumatics are usually in staggered relation to each other so that the air passages leading thereto and from their respective valves may be formed without interference with each other. It is, however, necessary to pass from the plane of the primary pneumatic into the plane of the secondary pneumatic in forming the wind passage from the valve controlled by the primary 30 pneumatic to the secondary pouch. This necessitates longitudinal channeling or angular boring, both of which are objectionable and increase the cost of construction. It is further necessary to pass this channel from 40 the top board of the wind chest in which the valves are located to the bottom board containing the pouches, and this is usually accomplished by extending the channel around through the outside wall of the chest, which 45 is a very indirect course.

With the present invention, I have both simplified and condensed the construction, first, by arranging a partition strip between the primary and secondary pouches, extending 50 from the top to the bottom of the valve chest, and forming a direct route for the air passages; and, second, in forming each air passage between the primary valve and secondary pneumatic in a single transverse plane, which is central with respect to the

primary pneumatic and intersects the cell of the secondary pneumatic.

In detail, A is the bottom board and B the top board of the chest. The bottom board A has mounted thereon a series of primary 60 pneumatic pouches C, which are preferably formed by buttons D, having stems D' secured in bores in the board A. The board A is also provided with a series of cells E for the secondary pneumatic pouches. These 65 pneumatics C and E are preferably arranged in staggered relation and adjacent to the opposite sides of the board A. F is a strip secured to the board A intermediate the pneumatics C and E and extending into contact with the upper board B. This strip is provided with a double series of vertical bores G and H, the former extending downward through the strip F and into the center of the board A, while the latter is extended 70 completely through the strip and board and the upper board of the power pneumatic I, which is arranged beneath the board A. The bore G is arranged in a transverse plane of the primary pneumatic C, and is connected 75 so with the valve cell J of the upper board B by a bore K extending from the outer edge of this upper board. The lower end of the bore G intersects with a transversely extending bore L in the bottom board A, this being arranged in the same transverse plane, and extending from the opposite edge of the chest.

Inasmuch as the primary and secondary pneumatics C and E are staggered in relation to each other, the bore L, which is in the 80 plane central with the primary pneumatic C, is offset from the center of the pneumatic E. The plane of the bore will, however, intersect the cell for the pneumatic E, and connection is made by a vertical bore M at one side 85 of the cell intersecting the bore L. Thus, a direct air passage is formed between the cell J and the cell of the pneumatic E by the bores K, G and L.

A direct connection is also formed between the cell N for the valve O operated by the secondary pneumatic and the power pneumatic controlled by said valve. This connection comprises the bore H, which extends through the strip F, board A, and top 105 board of the pneumatic I, and a registering bore P formed in the upper board, and which intersects with a lateral bore Q in said top board. This lateral bore is formed from the edge of the top board and intersects the valve 110

cell N, being preferably elongated in section, as shown.

The chest is completed by side strips R and S. The strip R has formed therein intersecting bores T and T', which communicate with the bore U, connecting with the primary pneumatic pouch C. The opposite edge of the side R closes the ends of the bore K. V are bleed passages formed in the strip R and intersecting with the bores T. The side strip S seals the ends of the bores L and Q and also completes the chest. Thus, when the parts are assembled, a vacuum chamber W is formed for the primary pneumatics. Upon the opposite side of the division strip F is another vacuum chamber X for the secondary pneumatics and valves.

With the construction as described, the parts may be readily assembled, the upper board being secured to the lower by screws passing through the division strip F and the side strips F and S being screwed or otherwise secured to the edges of the upper and lower boards. On account of the directness of the air passages, the action responds very quickly, and, by reason of the peculiar arrangement of the parts, the space occupied is reduced to a minimum.

What I claim as my invention is:

- 30 1. In a pneumatic action, a wind chest having passages in the top and bottom walls, primary and secondary pneumatics within said chest at the bottom thereof, valves operated by said pneumatics in the top of said chest, and a conduit intermediate said valves connecting the passages in the top and bottom walls of the chest forming in connection therewith a direct passage between one of said pneumatics and its controlling valve.
- 40 2. In a pneumatic action, a rectangular wind chest, parallel series of primary and secondary pneumatics and superposed valves extending longitudinally of said chest in staggered relation, passages formed by bores 45 perpendicular to the walls of the chest each passage located in the central transverse plane of one of said primary pneumatics and connecting with the corresponding secondary pneumatic at one side of its central plane.
- 50 3. In a pneumatic action, a wind chest, a pneumatic within said chest at the bottom thereof, a valve in the top of said chest, the top and bottom walls of said chest having passages therein, an intermediate strip between the top and bottom walls having a passage in alinement with said passages in the top and bottom walls whereby a continuous conduit is formed between said pneumatic and its controlling valve.
- 60 4. In a pneumatic action, a wind chest, primary and secondary pneumatics within said chest at the bottom thereof, valves in the top of said chest operated by said pneumatics, the top wall of said chest having a 65 passage therein connecting with said primary

valve, the bottom wall of said chest having a passage therein connecting with said secondary pneumatic, an intermediate strip between the top and bottom walls having a vertical bore in alinement with said passages whereby a conduit is formed between said primary valve and secondary pneumatic.

5. In a pneumatic action, a wind chest, primary and secondary pneumatics within the chest, said chest comprising a top wall having valve ports therein and bored passages communicating therewith, a bottom wall having bored passages therein leading respectively to the primary and secondary pneumatics and a strip forming a division in said chest having straight passages therethrough establishing communication between the passages in the upper and lower walls.

6. In a pneumatic action, a wind chest, primary and secondary pneumatics within said chest at the bottom thereof, valves in the top of said chest operated by said pneumatics, the top wall of said chest having passages therein connecting with said valves formed by intersecting bores respectively perpendicular to the end and bottom of said wall, the bottom wall of said chest having passages therein connecting with said pneumatics formed by intersecting bores respectively perpendicular to the end and top of said wall, an intermediate strip between the bottom and top walls having a vertical bore connecting with the bore in the top wall communicating with said primary valve and the bore in the bottom wall communicating with said secondary pneumatic forming a continuous conduit therebetween.

7. In a pneumatic action, a wind chest, a power pneumatic beneath the chest, primary and secondary pneumatics within the chest at the bottom thereof, valves in the top of said chest operated by said pneumatics, the top wall for said chest having passages bored therein communicating respectively with said primary and secondary valves, the bottom wall of said chest having passages bored therein communicating respectively with said secondary pneumatics and said power pneumatics, and an intermediate strip between the upper and lower walls having conduits therein, one of said conduits being in alinement with the passage in the upper wall communicating with the primary valve and the passage in the lower wall communicating with the secondary pneumatic and another of said conduits being in alinement with the passage in the upper wall communicating with said secondary valve and the passage in the lower wall communicating with said power pneumatic.

8. In a pneumatic action, a rectangular wind chest, a power pneumatic beneath said chest, parallel series of primary and secondary pneumatics and superposed primary

and secondary valves extending longitudinally of the case in staggered relation, the top wall of said chest having passages bored therein communicating respectively with 5 said primary and said secondary valves, the bottom wall of said chest having passages bored therein communicating respectively with said secondary pneumatic and, said power pneumatic, and an intermediate strip 10 between the upper and lower walls having vertical bores therein, one of said bores being in alinement with the passage in the upper wall communicating with the primary valve and the passage in the lower wall communi-

cating with the secondary pneumatic, and 15 another of said bores being in alinement with the passage in the upper wall communicating with said secondary valve and the passage in the lower wall communicating with said power pneumatic whereby continuous 20 conduits are formed between said members.

In testimony whereof I affix my signature in presence of two witnesses.

WILLIAM J. PUBLLOW.
